UNITED STATES PATENT OFFICE

ALEXANDER BOYNTON, OF SAN ANTONIO, TEXAS

STAGE-LIFT FLOWING DEVICE

Application filed November 16, 1927. Serial No. 233,691.

This invention relates to improvements in automatic stage lifts or flowing devices for wells, and it consists of the constructions, combinations and arrangements herein described and claimed.

An object of the invention is to provide a particular construction and combination of throttle bushing and plunger or control valve by operation of which the admission of lifting pressure fluid is so controlled as to admit the maximum volume of pressure fluid to the liquid column until a predetermined pressure differential is established, the plunger or valve being then automatically operable to gradually and progressively reduce the volume of pressure fluid admitted to the liquid column until the valve finally closes.

Another object of the invention is to make use of a differential plunger or valve element which is held in a full open position by the approximate equality of fluid pressure on each end of the element, thus permitting a maximum volume of pressure fluid to bypass it until a predetermined pressure differential becomes existent whereupon the throttling action begins.

Other objects and advantages appear in the following specification, reference being had to the accompanying drawing, in which,

Figure 1 is a vertical sectional view of the improved flowing device.

Figure 2 is an enlarged fragmentary sectional view illustrating details of construction to better advantage,

Figure 3 is a cross section taken on the line 3-3 of Figure 1,

Figure 4 is a detail sectional view of a slightly modified form of the valve element and co-acting throttle bushing, and

Figure 5 is a detail sectional view of a further modification illustrating an inversion of the arrangement in Figure 4.

Reference may be had to co-pending applications for Letters Patent for other further exemplifications of the invention herein dis-

closed, such application having been filed April 5, 1927, Serial No. 181,144 and filed August 24, 1927, Serial No. 192,049. It may be briefly stated that the present invention, as well as others of the same series, is concerned with the expeditious setting in motion and elevation of a column of liquid in a well. Although it is primarily sought to provide for the elevation of oil, yet the principle is equally well adaptable to the elevation of other liquid.

In the drawing the adjacent ends of a tubing string designated by sections 3 and 4 are screwed or otherwise fitted into the ends of the flowing device body 5. A lateral enlargement of the flowing device body has a chamber 6, known as the spring chamber. The spring chamber terminates at one end in a reduced portion 7 that communicates with a transverse outlet port 8 discharging into the bore of the valve body.

A bushing 9 extends past the outlet port 8 and into the passageway or chamber 11 in which the so-called differential plunger or valve element 12 is operable. The bushing has an opening 11a registering with the bore 8 and thus establishing communication between the bore and the passageway through the bushing.

A circular head 10, forming part of the bushing 9 is pressed into ultimate position at the base of the spring chamber 6 where, by engagement with the shoulders defined by the reduced portion 7, the bushing is held in proper fixed position. The foregoing valve element rests upon a hollow bushing 13 in the lower end of the passageway 11 when idle or during periods of equal pressure above and below it.

This plunger or valve element 12 has an outside diameter greater than that of the reduced portion 7. It is provided with a recess composed of straight-walled bores 14 and 15 and a connecting convexly-walled bore 20. The recess receives the extremity of the bush-

ing 9, and, as is later explained, the valve element rides over the dependent bushing as the former is lifted by by-passing pressure fluid.

The lower extremity of the bushing 9 is bevelled at 16 to agree with the corresponding formation at the bottom of the bore 15 to provide clearance but preferably not engagement. Similarly the upper extremity of the plunger 12 is bevelled at 17 to agree with the bevel 18 of the passageway or chamber 11, these corresponding bevels being for engagement. The dimensions of the parts may be such that the bevelled bottom of the bore 15 will engage the bevel or seat 16 to effect a sealing-off engagement, and at the same time the bevel 17 may engage the seat 18 for the same purpose.

However, the better practice is to avoid the engagement of the bevelled bottom of the bore 15 with the seat 16, and in order to prevent such engagement when the bevel 17 engages the seat 18 the bore 15 is preferably drilled to a sufficient depth to serve the intended purpose of avoiding this lower engagement.

It seems evident that if a seal-off between the bottom of the bore 15 and seat 16 is provided, as first suggested, the action of the spring (mentioned later) would tend to break the seal much easier and consequently at a much lower differential in pressure than if the seal-off occurs between the larger plunger end 17 and upper seat 18.

It is, therefore, thought best to avoid the possibility of a sealing-off engagement between the members 15 and 16 at a time when a sealing-off engagement might not be accomplished between the bevel 17 and seat 18. It is observed that, as already stated, the walls of the bore 15 are straight, but that these merge with the convex walls 20 of the adjacent bore, which walls are struck on the arc of a circle, the center of which is situated upon a plane by bisecting the axis of the plunger at a point where the bores 15 and 20 merge. The foregoing descriptive matter is illustrated in Figures 1 and 2 wherein the broken line 25 designates the plane perpendicular to the axis of the plunger, and 26 the center from which the arc is struck.

Situated in the chamber 6 is a spring 21 which falls short of a plug 22 closing the upper end. An axial extension 23 of the spring enters a counter-bore 24 in the plunger 12. It is to be observed that the length of the straight-walled bore 14 is exactly the same as the distance between the bottom end of the spring extension 23 and the bottom of the bore 24 plus the distance 27 between the upper end of the spring and the plug 22. This exact equality of the two distances is intended to compensate for the full movement of the plunger without allowing the inwardly arced surfaces or convex-walls of the bore 20 to

begin reducing or governing the volume of by-passing pressure fluid until compression of the spring 21 commences. If it should be desired that this governing action begin to act upon a smaller by-passing area, in order to admit less volume, then spring 21 or extension 23 thereof may be correspondingly shortened.

The reason of the foregoing arrangements is that the greatest volume of pressure fluid should be admitted to the liquid column at a time when the difference in pressures in the tubing and surrounding casing is very slight, and it is not until compression of the spring begins that there is any noticeable building up of a pressure differential. The volume of admitted pressure fluid can be best controlled by the arced bore 20 in association with the throttling bushing 9 to properly coordinate the difference in pressures in the tubing and the casing with the admission of lifting energy to do the required amount of work during such varying difference in pressures until such difference reaches a point where no additional energy is required to lift the liquid in the tubing at the desired velocity. It seems evident that the latter point is essential in determining the proper tension of the spring 21. This tension in turn, fixes the sealing-off point against the admission of further lifting pressure fluid.

In order that a better conception of structure may be had, the following dimensions of the fluid throttling mechanism will aid in the making of one exemplification of the flowing device: The walls of the bushing 9 are straight as shown, the outside diameter being .315", the inside 3/16". The diameter of the bore 14 is .340", leaving a limited but ample clearance between the bushing 9 and bore 14. The convex bore 20 is struck on a long radius, and the straight-walled bore 15 with which it merges is .318" in diameter, presenting a still greater limitation to the fluid flow when the plunger 12 rises so high that the end of the bushing 9 will occupy the bore 15. The diameter of the plunger 12 is .373", while that of the passageway or chamber 11 is 7/16".

Referring to Fig. 1: The greatest difference between the external diameter of hollow depending shank 9 and the internal diameter of bore in top of plunger should be .030". This difference in diameter is at the point of approximate contact between the two members as shown in Fig. 1, that is, about 1/16" below top of plunger. The smallest internal diameter of bore in top of plunger should be .005" to .010" greater than the diameter of depending hollow shank 9. This is at lowest point in plunger to which depending shank goes when plunger seals off upon its upper seat.

Referring to Fig. 2: The greatest diameter of the hollow section in the plunger should be .030" greater than the external diameter of

the depending hollow shank. This difference in diameters is at approximately $1/16''$ from the top of the plunger in the position shown. The difference in diameter between bottom bore 15 in the plunger and the depending hollow shank should be $.005''$ to $.007''$.

Referring to Fig. 4: The difference in diameter between the upper (largest) bore in top of plunger and the section over which it fits at point of engagement should be $.030''$.

10 The difference in diameters between the middle step in the hollow section of the plunger and the section over which it fits should be $.020''$. The difference in diameter between 15 the bottom step in the plunger bore and the section over which it fits should be $.010''$. The difference between the external diameter of the plunger and the plunger chamber should be $.020''$ to $.040''$.

20 Referring to Fig. 5: The difference between the top step of the plunger and the section in which it fits at engagement should be $.020''$. The difference in diameter between the second step of the plunger and the section in 25 which it fits should be $.030''$. The difference between the greatest external diameter of the plunger and the plunger chamber should be $.030''$.

30 The length of the coil section of the spring should be $5''$ to $6''$. The diameter of the spring should be $.100''$ to $.140''$ wrapped on a pitch of three to six coils per inch. The distance of the spring compression should be from $1/2''$ to $1''$. The diameter of spring coil should be $5/8''$ to $7/8''$.

35 Reference is made to Figure 4. Although this illustrates a modified construction yet it exemplifies the principle of operation in Figure 1. Here, as in Figure 1, the control means 40 is situated internally of the plunger or valve element. Instead of including a convexly walled bore as in Figure 1 the valve element 12 is provided with an intermediate straight-walled bore 28, the effect being a succession of 45 steps or counter-bores which progressively enlarge as they approach the bevelled edge 17.

50 Agreeable with the internal arrangement of the plunger the throttle bushing 9 has a plurality of external shoulders 29 which progressively enlarge toward the seat 18. The reader will observe at once that the co-action of the peculiar recess in the valve element 12 with the peculiar external arrangement in the bushing 9 must result in substantially the 55 same effect as in Figures 1 and 2.

Figure 5 illustrates what has been termed an inversion of the arrangement in Figure 4. The plunger or valve element 12 is provided with a plurality of external shoulders 30 which are of progressively smaller diameter, the smallest merging with the bevel 17 which can be recognized the same as the corresponding bevel in the other modifications.

Instead of now providing a pendent throttle bushing the upper end of the plunger

chamber 11 is reduced by a succession of counter-bores 31, the smallest of these merging with the bevel or seat 18. One difference in function is to be noted in respect to Figure 5; the pressure fluid will by-pass the plunger or valve element 12 more or less directly, whereas in Figure 4 and the preceding modification the pressure fluid is made to traverse a more or less tortuous course around the edge of the depending bushing 9.

I claim:

1. A valve comprising a body having a passageway, a valve element operable in the passageway by the pressure of fluid flowing therein, and co-acting surface formations in the valve element and a portion of the passageway defining a tortuous course for throttling the flow of said fluid.

2. A valve comprising a body having a passageway, a valve element operable in the passageway by pressure of fluid flowing therein, and associated and co-acting formations both in the valve element and the passageway, one of which formations includes a restriction in the valve element by which a throttling effect is upon the by-passing fluid upon an increase in the rate of flow of the fluid.

3. A valve comprising a body having a passageway with an inlet and an outlet, a tubular member in the body and having communication with the outlet, and a tubular fluid pressure responsive valve element closed at one end in the body and having telescopic association with the tubular member, the valve element being of a greater cross sectional area from its open end to a point intermediate its ends whereby a maximum quantity of fluid pressure will pass between the tubular member and valve element when the latter is in a predetermined open position, and the fluid pressure reduced when the valve element is in a second predetermined position, and means for resisting the movement of the valve element toward the tubular member.

4. A valve comprising a body having a bore with an inlet and outlet, a tubular member of less diameter than the bore received in the latter, and a fluid pressure actuated valve element in the bore having telescopic engagement with the tubular member and having one end closed and adapted to engage one end of the tubular member to prevent passage of pressure fluid through the outlet when subjected to a predetermined fluid pressure, and an expandable coil spring in the bore for resisting the movement of the valve element towards the tubular member after the former has moved a predetermined distance.

5. A valve comprising a body having a pressure fluid inlet and outlet, a tubular member in the body to one side of the outlet and having communication therewith, a tubular fluid pressure responsive valve element in the

casing having telescopic engagement with the tubular member and having one end closed and adapted to engage one end of the tubular member to seal the latter when the pressure element is subjected to a predetermined fluid pressure, the valve element being of different cross sectional area at different points along its length whereby variable fluid volumes are permitted to pass into the tubular member according to the position of the valve element.

6. A valve comprising a body having an inlet and an outlet, a tubular member in the body and having communication with the outlet, and a tubular fluid pressure responsive valve element closed at one end in the casing and having telescopic engagement with the tubular member, the valve element being of a greater cross sectional area from its open end to a point intermediate its ends whereby a maximum quantity of fluid pressure will pass between the tubular member and valve element when the latter is in a predetermined open position, and the fluid pressure reduced when the valve element is in a second predetermined position.

7. A valve comprising a body having a passageway, a bushing pendent in the passageway and forming part thereof, and a valve element operable in the passageway and telescoping the bushing, said element having a recess receiving the bushing, a portion of the recess being convexly formed to restrict the flow of fluid around the edge of the bushing as the valve element approaches said bushing.

8. A flowing device comprising a body having a passageway with an inlet and an outlet, a throttle bushing pendent in the passageway and communicating with the outlet, and a hollow plunger in the passageway, movable over the bushing under fluid pressure but being internally formed part way to permit an initial fluid flow of relatively great volume and a succeeding progressive diminution of the fluid volume as the plunger advances upon the bushing.

9. A flowing device comprising a body having a passageway with an inlet and an outlet, a throttle bushing pendent in the passageway, and a plunger movable in the passageway over the bushing under the influence of fluid pressure, having a bore with a restricted portion for throttling the fluid flow, and having a straight-walled portion permitting an initial flow of relatively great volume before said constriction takes effect.

10. A flowing device comprising a body having a passageway with an inlet and an outlet, a throttle bushing pendent in the passageway, a plunger movable in the passageway by pressure fluid entering the inlet, having a constricted bore with an introductory straight-walled portion to receive the bushing, and yieldable means permitting an initial free movement of the plunger in respect to

the bushing to the approximate extent of the straight-walled portion to permit an initial fluid flow of relatively great volume, being in position for engagement by the plunger to then retard the movement of the plunger as the constriction advances over the bushing.

11. A flowing device comprising a body having a passageway with an inlet and an outlet, a throttle bushing pendent in the passageway, a plunger movable over the bushing by pressure fluid entering at the inlet, said plunger having a constricted bore with an introductory straight-walled portion of larger diameter and a final counter-bore, a spring having an axial extension into the plunger stopping short from the bottom of the counter-bore a distance approximately equal to the distance between the end of the bushing and the beginning of the constriction, permitting an initial free movement of the plunger and an initial fluid flow of greatest volume before the plunger is put under restraint by engagement with said extension and the fluid flow is restricted as the plunger advances over the bushing.

12. A flowing device comprising a body having a passageway with an inlet and an outlet, a throttle bushing pendent in the passageway, a plunger which has an introductory straight-walled bore of largest diameter with an immediately following constricted portion that will reduce the volume of bypassing fluid as it advances upon the bushing, and yieldable means which stands in position to permit the initial advance of the straight-walled portion upon the bushing, before the plunger engages therewith, said means being subject to adjustment so that the plunger may move a greater or lesser extent before said engagement.

13. A valve comprising a body having an outlet, a passageway with an inlet and a pendent throttle bushing in communication with the outlet, and a hollow plunger receiving the end of the bushing and providing an increasingly lengthening by-pass as the plunger advances upon the bushing under the influence of pressure fluid entering at the inlet.

14. A valve comprising a body having a passageway with an inlet and an outlet, a throttle bushing pendent in the passageway and communicating with the outlet, and a plunger in the passageway, being made hollow by a bore which has an introductory straight-walled portion and a succeeding convex-walled portion receiving the bushing and producing a progressive throttling action upon by-passing fluid after the plunger advances sufficiently far to bring the end of the bushing into the region of said convex-walled portion.

15. A valve comprising a body having a passageway with an inlet and an outlet, there-

being a seat adjacent to the outlet, a throttle bushing pendent in the passageway and communicating with the outlet, and a plunger having separated straight-walled bores with 5 a connecting convex-walled portion, the end of the plunger adjacent one of the bores being bevelled to engage the seat when the plunger has advanced upon the bushing sufficiently far to introduce the end of the bush-
10 ing into the other bore.

Signed at San Antonio, in the county of Bexar and State of Texas this 19th day of October, A. D. 1927.

ALEXANDER BOYNTON.
